ASH TRAY

Cornelius Hendricks, Grand Rapids, Mich., assignor to Applied Arts Corporation, Grand Rapids, Mich., a corporation of Michigan

Application April 29, 1946, Serial No. 665,803

2 Claims. (Cl. 220—18)

1

This invention relates to an ash tray of the type which is mounted upon the dash of an automobile and tiltable outward for the deposit of ashes and other refuse in a receptacle provided therefor, which receptacle is removably mounted at the back of a tilting door. With my invention, the tilting door may be assembled on the dash so as to lie flush with its outer surface, being tiltable outwardly by pressure against the lower end portion of the door; and the door with the receptacle connected therewith, is pushed back to closed position by pressure at the upper part thereof, and in either position of the door, it is yieldingly held against movement. Furthermore, with my invention, the entire structure and its frame mounting, may be assembled on the dash of the automobile from the back. Novel means are further provided for limiting or stopping the downward movement of the removable receptacle with reference to the door on which it is mounted, and a novel yielding pressure means is provided for pressing against laterally extending guide flanges which are slidably received by guides on the door into a snug, yet yielding, engagement therewith, eliminating all rattling yet at the same time, permitting removal and replacement of said receptacle without binding or requiring the exertion of excessive force for such removal and replacement. The construction is also very readily produced at low cost and is substantially noiseless in operation. My invention attains all of these ends and functions set forth, as well as others, which will appear upon an understanding of the structural embodiment of my invention shown in the accompanying drawings, in which.

Fig. 1 is a vertical section through the ash tray or receptacle structure at its closed position.

Fig. 2 is a rear elevation thereof.

Fig. 3 is a view somewhat similar to Fig. 1 with the ash tray tilted to open position.

Fig. 4 is a horizontal section through the structure shown in Fig. 1.

Figs. 5 and 6 are fragmentary, vertical sections showing the lower portion of the supporting frame and receptacle carrying door mounted thereon in closed and open positions of the door, respectively and,

Fig. 7 shows in perspective the ashes receptacle carrying door and the receptacle separated from each other.

Like reference characters refer to like parts in the different figures of the drawings.

The dash of an automobile body, indicated at 1, has a rectangular opening normally closed by the tilting door referred to, which opening at its 55

vertical side edges has short rearwardly struck flanges 2, at its lower end a horizontal ledge 3 and at its upper end an upper flange which is turned horizontally to the rear and thence downward as indicated in 4 and thence extended back of the dash in a short curved section 5 as shown. The several flanges and ledges 2, 3, 4 and 5 are struck and pressed to the back of the dash 1 from the metal of which the dash is made.

10 An open frame upon which the receptacle carrying door is tiltably mounted is made from a length of flat metal with an upper side 6, two vertical sides 7 extending downwardly from the ends of the upper side and a horizontal bottom 8 furnished by bending inwardly toward each other terminal sections from the lower ends of the vertical sides 7. The upper side 6 is located at the under side of the previously described extension 5. At the under side of the upper member 6, a curved cover member 9 is located which, at its forward edge, has an up-turned lip on which a U-shaped channel of rubber 10 may be placed, being located underneath the part 4 and at the uppermost portion of the opening in the dash at which the door is located. A bolt 11 is used to secure the parts 5, 6 and 9 together in fixed relation to each other.

15 The lower side parts 8 are located underneath the horizontal ledge 3, and underneath them a stop for the tilting door is located, including a horizontal section 12 which, at the back of the frame, is bent to extend upwardly and outwardly in a section 13, which may have a rubber bumper 14 similar to that at 10 mounted at its free edge, against which the lower edge of the door is stopped when it is tilted outwardly. The sides 7 of the frame at their edges nearest the dash opening have each a projecting ear 16 integral therewith.

20 The door comprises an outer plate 17 conforming with the shape of the dash 1 and flush with its outer surface and of a size to substantially fill the opening made in the dash. Said door at its upper and lower edges is bent back upon itself to make upper and lower beads 18 and 19, and at each side edge is bent to provide side flanges 20 which extend into the opening and from which ears 22 extend inwardly adapted to be positioned along side the ears 16 for the pivotal connection of said ears to each other, thereby tiltably mounting the door to turn about a horizontal axis. The flanges 20 above said ears 22 are turned inwardly toward each other providing guides 21, one at each vertical side edge of the door as best shown in Fig. 7. A flat sheet metal plate 23 at its upper edge is

received within the upper bead 19 and is located back of the guides 21. It extends for its full width a short distance below the ends of said guides, is then reduced in width and adjacent each side edge is formed with a horizontal tab 24 to rest upon the pivot shaft which extends through the ears 16 and 22, thereby holding said plate in upper position and against down movement. The plate is narrowed at its lower portion and extends downwardly a short distance as at 25 and terminates in a horizontal outwardly bent lip 26 which reaches to the inner side of the plate 17. Between said outside door plate 17 and the inner plate 23 described a yielding spring frame 27 is located of the shape best shown in Fig. 7, which has bowed sides and ends which act to normally press the plate 23 snugly against the guides 21.

A pivot rod 28 passes through the ears 16 and 22 and is headed over at each end for permanency in construction, located immediately below the tabs 24. Two springs 29 of the form and shape best shown in Figs. 5 and 6, have one of the arms of each of said springs secured to the ears 22 and the other arms thereof to the vertical sides 1 of the frame described. In moving the door from open to closed position or vice versa, the lines of force of said springs pass from one side to the other of the axis of the rod 28, thereby yieldingly holding the door in either its closed or open position. When the door is closed, it strikes at its upper end against the bumper 10 and when opened against the bumper 14 which, being of noise deadening material, reduces noise of door operation.

The immediate ash receiving receptacle has a front 30 of sheet metal, the upper portion of which, at its side edges, is provided with slidable guide lips 31 adapted to be received between the plate 23 and the guides 21. At the upper end of the plate 31 a horizontal inwardly extending flange 32 is made. At the lower portion of the receptacle the metal from which the front is made is curved a distance to the rear at 33, then extended downwardly in a vertical lower front portion 34, and terminates in a horizontal bottom 35 (Fig. 1). The back 36, also of sheet metal, has two sides 37 extended forwardly therefrom, each of which at its upper portion, back of the lips 31, is shaped to provide a vertical channel 38 (Fig. 4), and is permanently secured to the front member 30. The lower ends of the back and sides have inwardly turned flanges at their lower edges passing underneath the bottom 35 to which they are permanently secured. The upper edges of the sides 37 are pressed outwardly and then back to form beads 39 which may be grasped by the fingers for handling the receptacle in its removal from and replacement upon the door.

It is evident that with this construction, the receptacle is very quickly and easily removed and replaced, the lower ends of the lips 31 entering between the upper ends of the guides 21 and the

plate 23, the upper portions of said guides being flared for ease of entrance, and that the receptacle is stopped in its downward movement by engagement of the bottom of the front upper portion of the receptacle against the ears 24, which in turn are stopped against the upper side of the rod 28. The door with the receptacle attached, when in closed position, has its outer surface flush with the surface of the dash 1. It is easily turned to open position by pressure against it below the rod 28 and is returned to closed position by pressure against its upper outer portion, the springs 29 serving to normally hold the door in either position to which it may be moved. The door is stopped at both its closed and open positions and the noise of engagement against the stops is deadened. The removable receptacle is maintained against rattling through the action of the spring frame 27 against the plate 23. The construction is very practical, and readily and easily manufactured in large quantities at very reasonable cost.

The invention is defined in the appended claims and is to be considered comprehensive of all forms of structure coming within their scope.

I claim:

1. An ash receiver comprising a frame, a cover pivoted near its lower end to said frame, inturned guide flanges on said cover and spaced rearwardly thereof, a plate interposed between said cover and said guide flanges, a spring interposed between said cover and said plate and acting to thrust said plate toward said guide flanges, a receptacle having outturned flanges slidably inserted between said plate and said guide flanges, said spring being of spring wire formed into rectangular shape, two opposite sides of which are bowed out of the plane of the rectangle, and a detent on said plate hooked under the lower end member of the spring.

2. The elements of claim 1 in which the pivot of said cover includes a pivot rod extending adjacent said plate and said plate is provided with a detent in engagement with said pivot rod, and a rearward downturned flange at the upper edge of the cover, the upper edge of the plate being located between the cover and flange.
